UNITED STATES PATENT OFFICE.

JACOB KERSTEN, OF ALLEGAN, MICHIGAN.

RADIO LOUD SPEAKER.

Application filed May 15, 1926. Serial No. 109,211.

This invention relates to a sound amplifying construction designed to be used in connection with a radio loud speaker unit. It is an object and purpose of the present invention to make a device of this character in a simple and economical manner and one which will be attractive in appearance and with which blasting of sound at certain pitches thereof is completely obviated. The invention consists of novel constructions and arrangements of parts which will be fully understood from the following description taken in connection with the accompanying drawings, in which

Fig. 1 is a front elevation of the sound amplifier.

Fig. 2 is an enlarged vertical section through the outer housing or shell of the structure shown in Fig. 1, substantially on the plane of line 2—2 of Fig. 1, the amplifying horn within said shell being shown in side elevation except for the lower end which is in section.

Fig. 3 is a horizontal section on the plane of line 3—3 of Fig. 4.

Fig. 4 is a front elevation of the amplifying horn which is located within the enclosing housing, and

Fig. 5 is a fragmentary vertical section through the lower part of the horn, housing and base, in a plane at right angles to Fig. 2.

Like reference characters refer to like parts in the different figures of the drawing.

In the construction of the sound amplifying apparatus an outer housing is used which includes two conical parts, the back 1 and the front 2. These parts are preferably formed of paper but the type of material used is not controlling in any respect and the same may be pressed from bakelite or otherwise made. The back 1 and the front 2 at their edges where they are placed together have annular projecting lips 3 which when the two parts of the housing are brought together lie against each other. The front 2 is provided with a plurality of openings 4 which may be of any suitable design and on the inner side of said front 2 an open mesh fabric 5 is secured. The two parts of the housing are held together by an annular clamping ring 6 preferably of sheet metal which has a groove at its inner side to receive the lips 3 and is securely clamped thereagainst.

The amplifying horn is located within

said housing. The horn comprises a downwardly extending neck 7 which extends below the lower side of the housing for a short distance, and a body which lies wholly within the housing. The body of the horn connects with the upper end of the neck, progressively enlarging as it extends upwardly and to one side from said neck, as indicated at 7^a, thence curving upwardly and laterally and then back in the opposite direction, and having a front side 8 terminating a short distance to one side of a vertical plane passing through the axis of the neck 7. The back side 10 of the body is extended farther and curved downwardly, as shown, and to a side of the portion 7^a a section 11 integral with the back 10 is located terminating in the forwardly and laterally curved lip 12. For reinforcement purposes a web 9 of paper or other suitable material is cemented between said lip 12 and the adjacent portion 7^a of the horn.

This horn, as thus made, extends upwardly and to one side from the neck 7, is then curved in the opposite direction to the other side, the front terminating short of the termination of the back 10 so that a relatively wide front opening for the escape of sound waves is made.

When the horn is placed within the housing it substantially fills the same, the back 10 thereof coming against the inner side of the back 1 of the housing, while parts of the front side of the horn come against the inner side of the front 2 of the housing between the openings 4 and are cemented thereto. This makes a very firm structure and one incapable of excess vibration in so far as possibility of blasting is concerned, yet acts in a measure as a sounding board to amplify, modulate and control the sound emitted.

The combined horn and housing therefore is supported on a pedestal 13 which is formed with an enlarged recess 14 at its lower side with a vertical opening 15 extending upwardly through the pedestal from the recess into which the neck 7 of the horn extends, the lower edges of the housing being received in a seat formed in the upper side of the pedestal. A loud speaker unit 16 is adapted to be located in the recess 14 from which a tube 17 extends upwardly into the lower end of the neck 7. A plate 18 connected with the tube 17 is permanently

secured by screws or other fastenings to the pedestal and holds the loud speaker unit in place.

In Fig. 5 a different form of the construction, in so far as the lower end of the horn and its manner of attachment to the pedestal is concerned, is shown and this form is one which, for several reasons, is preferred. The pedestal 19 is a hollow casting of metal, 10 preferably aluminum for lightness, across which at its lower portion a cross bar 20 extends having an opening through which an upper threaded outlet 21 to the loud speaker unit 16 projects, threading into the 15 lower end of the neck 22 of the horn which, in this case, is of metal, preferably aluminum, and is formed with an annular shoulder 22^a which bears against the upper side of the cross bar 20 around the opening there- 20 through. The upper end of the neck portion 22 is bent laterally as indicated at 23 and joins with the gradually enlarging section 7^a of the horn. Otherwise the horn is of the identical construction shown in Fig. 4. 25 The pedestal 19 is of greater height than that shown at 13 so that the neck 22 is of greater length than the neck 7, this providing a longer column of air into which the sound waves are directed. The assembly is 30 very simple requiring only the positioning of the lower end of the neck 22 through the opening of the bar 20 and the attachment of the loud speaker unit by screwing projection 20 into the lower end of said neck, this 35 serving to bind the parts securely together.

This invention of loud speaker unit has been perfected after long experiment and trial and has proved especially practical and useful. The sound passing from the mouth 40 of the horn is directed outward through the openings 4 in front of said mouth. The extension to the back side 10 of the horn beyond the front side with its dished formation is a feature of the construction which 45 is very desirable and necessary for the attainment of the best results. It directs the sound forwardly and by reason of its secure attachment to the back of the outer enclosing housing, makes a substantial sound 50 board in which excess vibration does not occur while vibrating in synchronism with the sound waves to properly reproduce and amplify the same. Uncontrolled and harmful vibrations are eliminated. The invention 55 is defined in the appended claims and is to be considered comprehensive of all forms of structure coming within their scope.

I claim:

60 1. An amplifying horn comprising a body and a neck extending downwardly from the body, said body of the horn being turned laterally and curved upwardly and over said neck and progressively enlarged as it ex- 65 tends away from said neck, and having front

and rear sides, the rear side being extended beyond the front side and having concave form.

2. An amplifying horn comprising, a neck of metal to the lower end of which a loud speaker unit is adapted to be attached, said neck having its upper portion turned upwardly and laterally at an angle to the vertical, and a body connected to the upper end of the neck and curving upwardly and laterally away therefrom and thence back over said neck, with the rear side of the body extended downwardly and outwardly beyond the front side thereof and formed with a concaved shape. 70

3. In a construction of the class described, a housing comprising two conical housing members having their base edges located against each other, means for securing said members together, the front member being formed with openings therethrough, and an amplifying horn located in the housing having a neck extending through the lower side of said housing and within the housing being turned laterally and upwardly and enlarged progressively away from said neck, the front and rear sides of the horn flaring outwardly to engage against the inner sides of said front and rear members of the housing, and the rear side of the horn extending beyond the front side thereof and formed into concave shape, substantially as described. 85

4. A construction containing the elements in combination defined in claim 3, said rear side of the horn where it engages against the inner side of the rear member of the housing being cemented thereto, substantially as and for the purposes described. 90

5. An amplifying construction comprising a hollow housing, a horn located within said housing and having a neck extending through the lower side thereof, said horn being curved laterally and upwardly away from the upper end of the neck and enlarging progressively away from said neck and having front and rear sides bearing against the front and rear sides of the housing, the rear side of the horn being extended beyond the front side and formed into concave shape, and said housing in front of the horn having openings for the escape of sound. 105

6. A construction containing the elements in combination defined in claim 5, combined with an open mesh fabric secured at the inner side of the front side of the housing and across the openings therein. 110

7. In a sound amplifier, a horn having a depending neck, said horn bending laterally to one side from the upper end of said neck and curving upwardly and over said neck and enlarging progressively away therefrom, the front side of the horn terminating short of the rear side, which rear side is extended downwardly and beyond the front 115 120 125 130

side and formed into concave shape, and a member of conical form lying against and secured to the rear side of said horn, substantially as described.

5 8. In a sound amplifier, a housing comprising a conical back member and a conical front member located against each other and secured together at their edges, said front member having openings therethrough 10 and a horn substantially filling said housing and bearing against the inner sides of the front and back members and having a neck extending through the lower side of the housing.

15 9. An amplifying horn comprising a depending vertical neck and a horn structure

extending laterally and upwardly away from said neck, said horn structure enlarging progressively in a direction away from the upper end of the neck, and having a rear 20 side extended beyond and downwardly from the terminal edge of the front side and formed into concave shape, said depending portion of the back having an inner edge spaced a short distance from the adjacent 25 inner side of the horn, and means extending between and connected to said inner edge of the depending portion of said back and the adjacent portion of the horn, substantially as described.

In testimony whereof I affix my signature.

JACOB KERSTEN.
